UNITED STATES PATENT OFFICE.

JOHN J. MCINTYRE, OF HARTFORD, CONNECTICUT.

BALL-GRINDING MACHINE.

Application filed April 6, 1921. Serial No. 459,028.

To all whom it may concern:

Be it known that I, JOHN J. MCINTYRE, a citizen of the United States, residing at Hartford, in the county of Hartford and State of Connecticut, have invented a new and useful Improvement in Ball-Grinding Machines, of which the following is a specification.

This invention contemplates improvements in those machines which are provided for grinding metallic ball blanks to approximately final shape and size.

The object of the invention is the production of a machine of this character in which the action is such that the ball blanks will be rapidly and accurately fed, ground and discharged and the grinding members will wear uniformly so that their use may be continued until they are entirely worn away.

This object is attained by feeding the ball blanks to a rotatory carrier which conducts the blanks between an annular rotatory bed, desirably made of metal and an annular rotatory platen, desirably made of emery, which members are rotated in opposite directions and at different speeds, the axis of the carrier being eccentric to the axes of the bed and platen so that the path of the blanks 20 will be completely across the oppositely rotating annular grinding surfaces. This path of the blanks subjects them to the action of three different forces,—that of the bed rotating at one speed in one direction, that of the platen rotating at a much higher speed in the opposite direction and that of the carrier which rotates at a still different speed and carries the blanks eccentrically between the grinding surfaces, the effect of which insures the accurate reduction of the blanks and uniform wear on the grinding surfaces.

In the accompanying drawings Figure 1 shows a front elevation of a machine which embodies the invention with parts cut in central vertical section. Figure 2 shows a horizontal section on the plane indicated by the dotted line 2—2 on Fig. 1. Figure 3 is a horizontal section on the plane indicated 40 by the dotted line 3—3 on Fig. 1.

The annular bed 1, which is commonly formed of cast iron, is fastened to the upper surface of a gear 2 that is mounted so that it may turn on the annular track 3, located 50 on the top of the frame 4. The gear is engaged by a pinion 5 fastened to the upper

end of a vertical shaft 6 supported by the frame. This shaft has a bevel gear 7 that meshes with a bevel gear 8 on a horizontal shaft 9 which is provided with a pulley 10. 60 This pulley is belted to a pulley 11 on a horizontal shaft 12 which is provided with a driving pulley 13.

The annular grinding platen 14 commonly formed of emery is fastened to the under- 65 side of a disk 15 which is secured to the lower end of a vertical shaft 16 that at its upper end has a driving pulley 17. This shaft is supported by bearings on the front of a bracket 18 mounted on the top of the 70 frame. The upper portion of the shaft passes through a bushing 19 which is threaded at its lower end. Fitted on the threaded end of the bushing is a sleeve 20 provided with radial pins 21 by means of 75 which it may be turned. Fastened to the lower end of the sleeve is a plate 22 on which rests a collar secured to the shaft. By screwing the sleeve up and down, the shaft may be raised and lowered for adjusting the distance between the annular working faces of 80 the grinding platen and bed. The axes of the platen and bed are coincident and the platen is designed to be rotated in one direction at relatively high speed while the bed 85 is designed to be rotated in the opposite direction at considerably lower speed.

The ball blanks are deposited in a hopper 24 located on the top of the frame and are fed through a spout 25 into perforations 26 90 arranged annularly near the edge of a thin metallic disc 27 that extends between the working faces of the bed and platen. This carrier disc is fastened to the upper end of a vertical shaft 28 that is supported near its 95 upper end by a bushing 29 in the top of the frame and supported near its lower end by anti-friction bearings 30 arranged above a boss 31 which projects upward from the bottom of the frame. On the shaft 28, 100 which is arranged eccentrically with relation to the axes of the grinding platen and bed, is a worm gear 32 that is engaged by a worm 33 on the horizontal driving shaft 12.

Beneath the carrier plate on the feed side 105 of the annular bed is a plate 34 for supporting the ball blanks until they pass between the grinding surfaces and located in the platen is a ring 35 which prevents the blanks from jumping out of the carrier as they pass 110 inside of the grinding surfaces. This ring is fastened to the lower ends of rods 36

which are loosely retained by the platen carrying disc and are connected at their upper ends by a ring 37. The blanks are free to drop from the holes in the carrier plate after they have passed to the outside at the back from between the grinding surfaces.

The carrier disc is rotated very slowly beneath the feed spout and between the 10 working faces of the annular grinding platen and bed in the same direction as the rapidly rotated platen. The eccentricity of the carrier disc is such that the ball blanks are carried from the outside across to the inside 15 and then to the outside of the path of the grinding surfaces. In thus traveling, the blanks pass twice completely across the grinding face of the annular emery platen so that the entire face of that member is 20 uniformly worn down. As the blanks are subjected to the rolling action of the slow-running carrier disc, the more rapidly rolling action of the metallic bed plate and the still more rapidly rolling action of the emery 25 platen, they are reduced rapidly and accurately to very nearly final spherical shape and size.

The invention claimed is:

1. A ball grinding machine comprising 30 two rotatory annular grinding members with their axes of rotation coincident and having means for rotating the grinding members at different speeds, a rotatory ball blank carrying member with its axis of rotation 35 within the circumference of the grinding members but eccentric to the axes of both the grinding members, said carrying member having spaced openings adapted to receive and carry ball blanks across and be-

yond the working faces of both the grinding members, and means for rotating the carrying member continuously between the grinding members. 40

2. A ball grinding machine having an annular rotatory bed member, an annular rotatory platen member, a rotatory carrying member with its axis eccentric to the axes of the bed and platen members and adapted to carry ball blanks between and across the working faces of said bed and platen members, a blank support below a section of the carrying member outside of the bed and platen members and a blank retaining member above the section of the carrying plate inside of the bed and platen members. 45 50 55

3. A ball grinding machine having a rotatory annular bed, means for rotating the bed at one speed, a rotatory annular platen, means for rotating the platen at a high speed and in the opposite direction from the bed, means for adjusting the space between the working faces of the bed and platen, a rotatory carrier with spaced openings for positively carrying ball blanks between the bed and platen, the axes of said bed and platen being coincident, and the 60 65 axis of the carrier being eccentric thereto, and means for rotating the carrier.

4. A ball grinding machine having a rotatory annular bed, a rotatory annular 70 platen, a rotatory carrier with annularly located blank receiving perforations the axis of said carrier being arranged eccentrically of the axes of the bed and platen and means adapted to rotate the bed, platen and carrier at different speeds. 75

JOHN J. McINTYRE.
